UNITED STATES PATENT OFFICE.

CHRISTIAN G. SORENSEN AND WILLIAM T. ALDEN, OF GRAND ISLAND,
NEBRASKA.

MAIL-BAG CATCHER.

SPECIFICATION forming part of Letters Patent No. 670,693, dated March 26, 1901.

Application filed December 18, 1900. Serial No. 40,262. (No model.)

To all whom it may concern:

Be it known that we, CHRISTIAN G. SORENSEN and WILLIAM T. ALDEN, citizens of the United States, and residents of Grand Island, in the county of Hall and State of Nebraska, have invented new and useful Improvements in Mail-Bag Catchers, of which the following is a full, clear, and exact description.

This invention relates to a mail-bag catcher which is designed to deliver bags respectively from and to a car and to avoid the necessity of throwing the bag from the car to the ground by providing mechanism for catching the bag which is delivered from the car and holding it safely until removed by an attendant.

This specification is a specific description of one form of the invention, while the claims are definitions of the actual scope thereof.

Reference is to be had to the accompanying drawings, forming a part of this specification, in which similar characters of reference indicate corresponding parts in all the views.

Figure 1 is a perspective view showing the operation of the invention. Fig. 2 is a side elevation of the crane which is arranged alongside of the track. Fig. 3 is a plan view of the same, and Fig. 4 is a detail view of the catch for the lower ring of the mail-bag on the train.

The mail-car is provided, at the bottom of the door therein, with a horizontal bar *a*, extending longitudinally of the train and carrying an adjustable arm *a'*, with a T-shaped outer end, to the bottom of which springs *a*² are attached to hold the lower ring of the mail-bag, as indicated in Fig. 1. At the upper part of the door is mounted the device for holding the upper end of the bag and also for catching the bag which is to be delivered to the car. This device comprises a rod or bar *b*, mounted to rock in bearings *b'*, attached to the car at the sides of the door. The bar *b* has a handle *b*², to which is connected a chain *b*³, which extends downward and has a hook on its end to engage with an eye *b*⁴ on the floor of the car, so as to hold the apparatus in the horizontal position. (Shown in Fig. 1.) This chain, however, permits the arm *b*² to be thrown downward to raise the outer part of the device and also prevents

the outer end, which holds the sack, from dropping downward. Two struts *b*⁵ project outward from the rod or bar *b* and carry a fork *c*, which is adapted to engage the mail-bag that is to be delivered to the car. This fork *c* has at its rear end a cross-piece *c'*, carrying a stud and spring *c*² for removably holding the upper ring of the mail-bag, and passing rearward of the stud and pin *c*² is a shield or guard *c*³, which serves to prevent the other bag from becoming engaged with and torn by the stud *c*².

d represents a post which is erected alongside of the track and adapted to carry the bag which is to be delivered to the train. This post has at its upper end a lever *e*, fulcrumed thereto and provided with oppositely-projecting pins *e'*, adapted to engage the upper ring of the mail-bag. The other end of the lever *e* has a chain *f* connected therewith, which passes downward to and into connection with an arm *g*, which is hinged at the point *g'* to the post *d*. This arm *g* is provided with braces *g*² at its sides, such braces being fastened rigidly to the arm and being hinged to a horizontal cross-piece *g*³, fastened to the post *d*, this cross-piece being braced by straps *g*⁴, attached to the post, as shown. The outer end of the arm *g* is strengthened by a reinforce-plate *g*⁵, and this plate is formed with a socket therein, which is adapted to receive the shank *h*' of the fork *h*. This shank *h*' is removably fitted in the said socket of the arm *g*, so as to permit the reversal of the fork *h*, thus placing it in position to carry mail-bags which are to be taken by a train running in either direction. The two pins *e'* are provided for the same purpose. The arrangement shown in the drawings is adapted for operation when the train is running in the direction indicated by the arrow shown in Fig. 1; but if the train were running in the other direction the parts would be correspondingly reversed, as will be obvious.

A mail-bag hung on the devices for the car has its lower ring engaged with the appropriate end of the T on the arm *a'* and its upper ring engaged with the stud and spring *c*². The mail-bag which is to be delivered to the car has its lower ring engaged with the shank *h*' of the fork *h* and its upper ring engaged

with the corresponding pin e' . The bag thus arranged supports the arm g in horizontal position. When the bag is removed, the arm g drops and drawing on the chain f it throws 5 the lever e into approximately vertical position, as indicated by the dotted lines in Fig. 2. As the car approaches the post d the fork h engages the bag on the car, and the bag is thus snatched from the holding appliances on 10 the car. Simultaneously the fork c engages the bag at the post and removes the same from the holding devices thereof.

Having thus described our invention, we claim as new and desire to secure by Letters 15 Patent—

1. In a mail-bag-catcher apparatus, devices for attachment to a car, comprising a fork to engage the mail-bag which is to be delivered to the car, and holding devices for the ends of 20 the mail-bag which is to be delivered from the car, the upper holding device being located at the throat of the fork and the fork having a guard passing around the said upper holding device to protect the same.
- 25 2. A mail-bag catcher having supporting devices for the upper end of the bag, a fork provided with a shank, and means in which the shank is removably received, the shank of the fork serving to hold the lower end of 30 the mail-bag, and the fork serving to receive a second mail-bag.
3. A mail-bag catcher, having a post, means for carrying the upper end of the mail-bag,

such means being mounted on the post, an arm also mounted on the post, and a fork with 35 a shank removably fitted in the arm, the shank of the fork serving to carry the lower end of the mail-bag and the fork serving to receive a second mail-bag.

4. A mail-bag catcher, having a support, 40 and a fork with a shank removably fitted in the support, the shank serving to assist in holding one bag and the fork serving to catch another bag.

5. A mail-bag catcher, comprising a fork, 45 means for mounting the same on the car, and devices carried at the throat of the fork for holding the upper end of a mail-bag which is to be delivered from the car, the fork having a guard inclosing the holding devices to protect them. 50

6. A mail-bag catcher, comprising a fork adapted to be mounted on the car, means at the throat or rear end of the fork for sustaining a mail-bag, and a guard passed around 55 said means to protect therefrom the bag which is engaged in the fork.

In testimony whereof we have signed our names to this specification in the presence of two subscribing witnesses.

CHRISTIAN G. SORENSEN.
WILLIAM T. ALDEN.
